UNITED STATES PATENT OFFICE

JENS JOHANNES JENSEN, OF COPENHAGEN, DENMARK, ASSIGNOR TO BOGGILD & JACOBSEN, OF COPENHAGEN, DENMARK

MACHINE FOR CASTING ARTICLES FROM PLASTIC OR LIQUID MASSES

Application filed December 18, 1929, Serial No. 415,075, and in Denmark November 23, 1929.

It is commonly known that casting machines for casting articles on to a movable mould-carrying belt are adapted to cast such articles in different lengths, different quantities, and in different number of transverse rows, although the same length of time is used for each pouring, but the known casting machines are as a rule fitted with a swinging feeding hopper adapted to move along a continuously moving mould belt.

Such machines, however, are all quite costly to manufacture and require a great number of adjustable parts.

The present invention relates to a casting machine which enables the above mentioned variation in use, to be accomplished in an essentially simpler manner, than with machines commonly used for such purposes. In the present device, by using a stationary feeding hopper and a uniformly moving mould belt and other features which will be herein described, accomplishes the variations in casting, by a variation in the time of pouring the poured material which in turn determines the length of the castings poured, and the quantity of material poured at each pouring.

The present machine offers the further advantage that by varying the pouring time the castings may also be adjusted and varied according to the number of moulds in each plate, and with due regard to the distance between the last mould in one mould plate of the moving conveyor, and the first mould in the following mould plate.

As a special feature of the present invention, a stationary feeding hopper may be used in combination with an intermittently moving mould-carrying belt, whereby at the time of pouring, the mould being poured is temporarily held stationary; or said mould is moved at a speed corresponding to the length of the casting being poured, and the time necessary to pour the same.

It is for instance important that the feeding hopper be a stationary one, because when small articles are being poured, a swinging feeding hopper, has to perform so many pouring operations per minute, that difficulties of a practical nature occur, and rapid

oscillations of the hopper valves in combination with the great weight of said hopper strains the moving parts of the machine to an extent which shortens the life of said machine. The use of a stationary feeding hopper also permits a finer adjustment of the quantity poured, and as a result a greater uniformity in the weight of castings poured is attained.

By having the entire mould-carrying belt moving at a uniform speed it becomes possible to dispense with many of the devices commonly required for enabling one portion of the mould belt to be held stationary, while pouring is being effected, as it is evidently impracticable to stop the entire mould belt, which is often more than 300 feet long, whenever a pouring is made.

The invention consists in part of a feeding hopper and an endless mould belt moved normally at a uniform speed. The feeding hopper is fitted with a series of plungers and a valve, serving to regulate the supply of material to the pouring cylinders, and the discharge from the latter to the mould plates all in a heretofore well known manner. The present invention relates to a cooperation of the above named members in such a manner that the pouring period of the machine, and the quantity poured can be varied. By variation of the pouring period, a corresponding variation of the length of the casting being poured is attained, since this length is a function of the pouring period, and by varying the length of stroke of the plungers, of the pouring cylinders of the machine, the quantity of material poured can be varied, viz., the quantity of material pressed out of the pouring cylinders in a given unit of time can be varied.

The invention is shown on the drawings, in which

Fig. 1 shows one side of the casting machine, in side elevation;

Fig. 2 is a top plan view of Fig. 1;

Fig. 3 shows in side elevation, and at a larger scale, the suction position of the moving mechanism of the plungers, and the valves forming part of the machine;

Fig. 4 shows a similar side view, to that of

Figure 3, with the corresponding parts in a pressure position;

Fig. 5 shows a similar view to that shown in Fig. 1, but is of a somewhat modified type of construction of the device;

Fig. 6 shows in side elevation a combination of the stationary pouring hopper of the invention, with a mould-carrying belt, which is moved continuously, although the portion thereof situated directly below the pouring hopper, has an intermittent motion.

In the drawings the numeral 1 is a pouring hopper disposed above a frame 2 supporting an endless mould belt 3. The mould belt is moved from a driving roll or sprocket wheel 4, and the mould belt is supposed to be continued towards the left on the drawing as seen in Figure 1, where it may pass through various auxiliary appliances not shown, but often required by such a casting machine. For instance said belt may pass through an oscillating table, a cooling closet, or the like device. On the lower part of the pouring funnel 1 a bottom block 5 is attached, containing a series of pouring cylinders 6 and a series of valves 7. A shaft 8 is mounted in the frame 2 of the machine, and is fitted with two sets of cam discs 12a, 12b, 12c . . . and 13a, 13b, 13c driven from a driving shaft 11 by means of a gear-wheel transmission 9, 10. The said cam discs 12a, 13a etc., cooperate with rollers 14, 18 which are supported by arms 15, 19 etc., which in their turn are connected directly to the valve 7, and to the plunger rods 27 of the cylinders 6. The cam discs 12a, 12b, 12c . . . are in engagement with a roller 14 on an arm 15, from which a rod 16 extends to the crank 17 of the valve 7; and the cam discs 13a, 13b, 13c . . . are in engagement with another roller 18, on an arm 19, which is pivoted on a shaft 20. The arm 19 is also connected to a slotted lever 21. The slot 22 of arm 19 is fitted with an adjustable block 23, which last is engaged by the forked end of an arm 24, having its opposite end hinged to an arm 25. The arm 25 is rigidly mounted on a shaft 45. The same shaft 45 supports another arm 26, which is connected to a plunger rod 27, forming part of a plunger in the cylinder 6. It should be mentioned that since as a rule a number of pouring cylinders 6 will be situated side by side transversely of the machine, it must be understood that the arm 26 is not hinged directly to one of the plunger rods 27, but cooperates with a transversely disposed shaft 28, to which all the plunger rods are pivotally attached.

It is seen that by the herein described mechanism the length of stroke, of the plungers can be regulated and varied by displacement of the block 23 in the slot 22 of the arm 21, and as the shaft 8 always rotates at a uniform speed the quantity of material poured from the pouring cylinders can consequently be varied by adjustment of the hand wheel 46

which varies the position of block 23 in the slot 22. The variations in the motion of the valve 7 and of the pouring plungers 27, 27 are effected by adjustment of the two groups of cam discs 12a, 12b, 12c . . . and 13a, 13b, 13c . . . with relation to the rollers 14 and 18. This variation is effected by transverse axial displacement of the two groups of cam discs along the shaft 8. In order that such a displacement may take place the rollers 14 and 18 must be adapted to be moved from the cam discs during the axial displacement of the latter, and as shown by the drawings this is effected by means of the levers 29 and 30, the upper ends of which cooperate with arms 31, 32 connected to the above mentioned arms 15 and 19, while the lower ends of the two arms 29 and 30 are connected to a lever 33. By lifting the outer end of this lever 33, which is fitted with a handle 71, the rollers 14 and 18 can be moved from the cam discs, while the latter by means of an adjusting wheel 34 Fig. 2 can be displaced in axial direction, until the desired "set" of the various cam discs comes opposite the said rollers.

It will easily be understood that by using a greater or smaller number of cam discs 12a, 13b, etc., on the shaft 8 the number of pourings of material per mould plate, and the time for each pouring may be varied within very wide limits. In order to equalize the difference existing between the distance between the individual moulds on a mould plate, and the distance from the last mould on one mould plate, to the first mould on the following mould plate the cams of the cam discs may be situated at varying distances from one another as shown in Figs. 3 and 4. These two figures show one single set of adjacent corresponding cam discs arranged for two pourings of material into the moulds on each mould plate, and it will be seen in Fig. 3 that while the distance between the one cam 12', and the second cam 12' on the disc is of normal radial length, the distance between the second and the first cam may be longer or shorter corresponding to the longer or shorter time consumed from the moment when the last pouring into the last mould, on the first mould plate is effected, to the moment when the first pouring into the first mould, on the following mould plate has to take place.

As mentioned above Figs. 3 and 4 show two sets of cam discs, fitted with two cams 12' and 12'' corresponding to two pourings of material or pourings of two moulds. For each mould plate, the set of cam discs will be fitted with another "number" of cams on each disc, or with cams of different radial length, corresponding to the length of the casting and quantity of material which is to be poured.

As the adjustment from one set of cam discs to another set can be effected in exceedingly short time, merely one or two seconds,

it will be practicable to use different moulds with different spacings in the mould belt 3. There may for instance be two pourings per mould plate, on one part of the mould belt, and another number of pourings in another 5 part of the mould belt, the moving mechanism of the adjusting wheel 34 Fig. 2 being for instance arranged in such a manner that each revolution of the said wheel will displace the cam discs axially in a transverse direction a distance equalling the thickness of 10 one disc.

It is of course not sufficient to be able to determine the quantity poured, and the length 15 of casting, but the moulds must also be adjusted in such a manner that the material poured will reach the proper point in the moulds on the mould belt. For this reason 20 a fine adjustment of the mould belt 3 relatively to the pouring orifices of the pouring cylinders 6, 6 is required, and this adjustment is effected by means of the mechanism described below. In the base 2 of the machine 25 a carriage 35 movable in the longitudinal direction of the machine is provided. This carriage moves between guides (not shown), and its displacement can be effected by means of a threaded spindle 72 and a hand wheel 36 as shown in Fig. 1. The details pertaining 30 to this displacement, however, are not shown on the drawing. The carriage 35 supports two sprocket wheels 37 and 38, and the main frame 2 of the machine is further fitted with some guiding rollers 39, 40, 41 and 42. As 35 shown on the drawing the driving chain 43 of the conveyor belt passes over a sprocket wheel 44 Fig. 1, disposed on the shaft 11, thence beneath the guiding roller 39 and over the sprocket wheels 37 and 42, which serve to 40 drive the conveyor belt itself.

From the sprocket wheel 42 the driving chain 43, passes over the guiding rolls 41, 38 and 40 and up to the driving wheel 44. By displacement of the carriage 35 to the right 45 or to the left the position of the moulds of the mould belt 3 below the pouring orifices of the pouring funnel 1, may be varied within reasonable limits. The arrangement of the valve 7 itself forms no part of the present invention, but it may be mentioned here that the 50 said valve alternately effects communication between the pouring cylinders 6, and the feeder hopper 1, and the pouring orifices.

In the modified construction shown in Fig. 55 where the numerals of reference correspond to those used in Fig. 1 the crosshead 28 cooperates with a swinging arm 26 (as in Fig. 4) attached to a shaft 45 Fig. 5, which last supports another swinging arm 25 cooperat- 60 ing with a driving rod 24, the upper end of which is connected to an adjustable block 23, in the slotted arm 21. Arm 21 is journaled about a shaft 20 and is rigidly connected to an angular lever 19, the bent end 18 of which 65 cooperates with a disc 65, fitted with notches

63 and 64. This disc 65 is fixed on a shaft 8, which is maintained at a uniform rate of rotation by means of suitable power transmitting members, for instance a gear-wheel transmission 9, 10, 66 and 70.

By the here described arrangement the plungers 27 can be given a reciprocating motion, the length of stroke of which can be varied by varying the position of the sliding block 23 in the slot 22, of the slotted arm 21. The plungers 27 will make one double reciprocating stroke, whenever one of the notches 63 or 64 passes the end 18 of the bent lever 19. In the case shown in Fig. 5 the plungers will consequently make two double strokes for each revolution of the disc 65, as there are two notches on said disc corresponding to the provision of two transverse rows of moulds, on each mould plate mounted in the endless mould-carrying belt. If large castings are to be made, so that there can only be one transverse row of moulds on each mould plate, the disc 65 can be replaced by a notched disc having only one notch therein, and similarly when pouring has to be effected on to mould plates with three or more transverse rows of moulds in each plate, then the disc 65 can be replaced by other discs each fitted with a corresponding larger number of notches.

By means of a spring or the like, not shown on the drawing the end 18 of arm 19 is maintained in a pressing relation against the disc 65, so that when one of the notches 63 or 64 passes the end 18 of said arm, the said spring will maintain the arm pressed against the notched portion of said disc 65.

Although heretofore in this specification the assumption has been that the mould belt 3, was moving at uniform speed during the pouring operation, it may under certain circumstances be preferable to let the mould belt remain stationary during the pouring, or at any rate to let the one mould or one transverse row of moulds be held stationary, into which the pouring is being effected.

On the other hand it is of course impossible to impart an intermittent motion to a mould belt frequently more than 300 feet long, and an arrangement may therefore be made, whereby only the mould or transverse row of moulds into which the material is being poured, and the adjoining parts of the mould belt are held stationary, while the remaining part of the mould belt is kept moving at a uniform rate of travel.

Also it may also be of importance, when very long articles are being cast, to be able to impart, during the pouring operation itself, a more rapid motion to the particular mould or row of moulds into which the material is being poured, for the purpose of having the material better distributed over the entire mould.

Fig. 6 shows an arrangement for attaining this last named result. The mould belt 3, which is endless, is moved in the direction in-

dicated by the arrows on the mould belt. Supposing the empty mould belt, i. e. the belt freed from castings, to arrive from the left, then it will pass over a roller 48, and from 5 there over a roller 49, and over a roller 36. In the construction shown on the above mentioned Fig. 6, the roller 48 is to be considered as the driving roller. After having passed the roller 36 the mould belt 3, passes along 10 the top surface of an oscillating table 50, and after having passed below the bottom block 5 of the pouring hopper 1, and the oscillations have caused the poured material to be uniformly distributed in the mould, the mould 15 belt passes a roller 51. Thereafter the belt 3 passes around another roller 52, and is directed into a cooling closet (not shown). The rollers 49 and 52 are supported by arms 53 and 54, pivoted on the pins 55 and 56, and the 20 two arms 53 and 54 are interconnected by a rod 57. In rigid connection with the arm 54 an arm 58 is provided, which by means of an angularly disposed arm 59 is connected to another lever 60. The latter is pivoted on 25 the pin 56, and the extreme bent end 61 of said lever cooperates with a notched disc 67 on the shaft 68 supporting the guiding roller 48. The arm 59 is fitted with a slot 73, in which the arm 58 can slide, the position of the 30 arm 58 in the slot being adjusted by means of an adjusting screw 69.

The device shown in Fig. 6 operates in the following manner:

When a mould plate, in the mould belt 3 comes opposite the bottom block 5 of the 35 pouring funnel 1, and a pouring is effected there, the notched disc 67 moves the arm 60 upward, owing to the action of a spring (not shown on the drawing) the end 61 of the 40 arm 60 will slip into the notch in the disc 67. The levers 53 and 54 will as a result swing to the left as seen in Fig. 6 and cause the part of the mould belt situated above the rollers 49 and 52 to remain stationary. But 45 as soon as the notched disc 67 has been revolved so that the arm 61 is moved back to the right, to its opposite extreme position, then the rollers 52 and 49 will again be moved back to the right and the portion of the 50 mould belt situated between the said rolls will proceed at an increased speed, until the next mould on the mould plate is directly below the bottom block 5, at which moment the arm 60 once more will engage the notch 55 and the mould being poured will remain stationary.

When it is desired to increase the rapidity of the motion of the mould during the pouring operation, the notched disc 67 is replaced 60 by a cam disc (not shown), whereby the arm end 61, and with it the rollers 49 and 52 will be moved to the right as seen in Fig. 6 by said cam, and an accelerated motion will thus be imparted to the portion of the mould belt 65 3, located between the rolls 49 and 52.

By the herein described machine it is practicable, as shown by the above explanation, to vary all pourings inside of very wide limits, and to adjust the machine practically instantaneously from one kind of pouring 70 operation to another.

Having thus fully described the invention, what I claim as new and desire to secure by Letters Patent is:

1. In a casting machine, a frame, a stationary feeding hopper mounted thereon having a plurality of pouring cylinders arranged thereon, means for periodically feeding poured material out of said cylinders, and a moving conveyor having a plurality of moulds thereon adapted to receive poured material when placed in alignment with the respective pouring cylinders. 75

2. In a casting machine, a frame, a stationary feeding hopper mounted thereon having a plurality of pouring cylinders arranged thereon, means for periodically feeding poured material out of said cylinders, and a conveyor having a plurality of moulds thereon, and means for moving the conveyor 80 at a uniform, an accelerating and a retarding rate of speed, for the purpose of aligning the moulds beneath the respective pouring cylinders. 85

3. In a casting machine, a frame, a stationary feeding hopper thereon, a plurality of pouring cylinders arranged beneath the hopper, a valve for the respective cylinders, a plunger rod for each pouring cylinder, means for synchronously actuating the plunger rods and the cylinder valves, for the purpose of ejecting pourer material therefrom. 90

4. In a casting machine, a frame, a feeding hopper and a transverse revoluble cam-shaft mounted thereon, a plurality of pouring cylinders arranged beneath the hopper, a valve for each cylinder, a plunger rod for each cylinder, a series of adjacent cams arranged in pairs on the cam shaft, each pair of cams having means for actuating a cylinder valve and a piston in a synchronous manner, and means for revolving the cam shaft. 100

5. In a casting machine, a frame, a feeding hopper, and a revoluble cam shaft mounted on the frame, a plurality of pouring cylinders arranged beneath the hopper, a valve for each cylinder, a plunger rod for each cylinder, a series of adjacent cams arranged in pairs on the cam shaft, each pair of cams having means for actuating a cylinder valve and a piston in a synchronous manner, and means for revolving the cam shaft, a continuous belt conveyor having a plurality of moulds thereon, and means for moving said conveyor at a uniform, and varying rates of speed; for aligning the moulds beneath the respective pouring cylinder valves, and holding the said moulds in timed relation therewith for the pouring period of said valves. 115

6. In a casting machine, a frame, a feeding hopper, and a revoluble cam shaft mounted on the frame, a plurality of pouring cylinders arranged beneath the hopper, a valve for each cylinder, a plunger rod for each cylinder, a series of adjacent cams arranged in pairs on the cam shaft, each pair of cams having means for actuating a cylinder valve and a piston in a synchronous manner, and means for revolving the cam shaft, a continuous belt conveyor having a plurality of moulds thereon, and means for moving said conveyor at a uniform, and varying rates of speed, comprising a continuous belt, a pair of bent and vertically disposed arms mounted in the frame, each arm having a roller on its upper end, in engagement with the conveyor belt, and pivoted to the frame at its lower end, a driving roller shaft mounted in the frame, a driving roller for the belt on said shaft, a notched disc revolvably mounted on the roller shaft, a pivoted lever mounted in the base of the frame having an extension thereon in pressed engagement with the notched cam, a horizontal rod pivotally connected to the bent and vertically disposed arms, intermediate their length, and adjustable means for controlling the range of action of the pivoted lever with reference to the vertically disposed arms for increasing, stopping and increasing the speed of the belt conveyor, and means for operating the belt conveyor.
7. In a casting machine, a frame, a stationary feeding hopper mounted thereon, a plurality of pouring cylinders arranged beneath the hopper, means for periodically feeding poured material out of said cylinders, a moving mould carrying conveyor comprising, a continuous moving belt, and means for actuating same, a pair of bent and vertically disposed arms mounted in the base of the frame, each having a roller on its upper end in engagement with the conveyor belt, and pivoted to the frame at its lower end, a drive roller shaft mounted in base of the frame, a driving roller on said shaft, a cam disc revolvably mounted on the driving roller shaft, a horizontally disposed connecting rod pivotally joined with the pair of bent and vertically disposed arms intermediate their length, a pivoted lever mounted in the frame, operatively connected with the pair of bent and vertically disposed arms, and having an extension thereon in operative engagement with the cam disc for accelerating, stopping, and retarding the motion of the conveyor belt and permitting the moulds on same to be timed with reference to the period of pouring from the pouring cylinders of the machine.
8. In a casting machine, a frame, a feeding hopper on the frame having a plurality of pouring cylinders thereon, a valve in each cylinder, a piston and piston rod in each cylinder, means for periodically discharging
- poured material from said cylinders, comprising, a transversely disposed cam shaft on the frame, a plurality of cams, arranged in pairs on the cam shaft, continuously operated actuating means for revolving the cam shaft carried on the frame, a pair of rollers each of which is adapted to be placed in engagement with the respective members of each pair of cams, a slotted lever having a bent arm carrying one of the cam engaging rollers, adjustable means connecting the slotted lever and the piston rod for actuating same, a valve operating rod pivotally connected to the cylinder valve, means connecting the said rod with the valve actuating cam roller, and means for synchronously operating said cam rollers, to open the cylinder valve, and operate the piston rod, said means also being adapted to disengage the cam rollers from one set of cams and place them into engagement with other sets of cams located on the cam shaft for purpose of operating the pouring operation of the machine in a variable manner.
- In testimony whereof I affix my signature. 90
